UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

AUTO-REPAIR COASTER.

1,249,735.

Specification of Letters Patent.

Patented Dec. 11, 1917.

Application filed March 10, 1916. Serial No. 88,420.

To all whom it may concern:

Be it known that I, WILLIAM B. FOSTER, of Utica, in the county of Oneida and State of New York, have invented certain new and useful Improvements in Auto-Repair Coasters; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to auto repair coasters as low-lying trucks are called when particularly adapted to support a workman beneath an automobile.

The purpose of my present invention is to provide an auto repair coaster of improved construction and one well adapted to conveniently serve for the purpose intended.

A further purpose is to provide a device of the character described which is relatively light in weight but very strongly made and which is especially convenient for the operator to use.

A still further object of my invention is to provide a coaster wherein the supporting platform or surface is yieldingly mounted upon the frame of the coaster and further wherein said surface is composed of a relatively flexible material, whereby the supporting surface accommodates itself more or less to the operator's body and his movements while on the coaster.

Yet another purpose of my invention is to provide certain details of construction and combination of parts well adapted to provide a neat, durable and well-made article.

A still further purpose of my invention is to provide a coaster having a metallic frame and metallic corner pieces of such construction and combination that relatively large casters may be mounted upon the frame without increasing the height of the coaster from the floor; and also to have the parts of the auto coaster so constructed that the ordinary and well-known forms of casters

may have their supporting plates securely fastened to the coaster when being made without adding materially to the work necessary to assemble the coaster frame.

Further purposes and objects of this invention will appear from the specification and claim hereinafter set forth.

Figure 1 is a top plan view of an auto repair coaster embodying my invention.

Fig. 2 is a bottom or inverted plan view of said coaster.

Fig. 3 is a bottom plan view of one of the corner pieces used and Fig. 4 is an outer side view of the same part. Fig. 5 is a top plan view of a corner piece.

Fig. 6 is a bottom view of one of the corners. Figs. 3-6 are drawn on a larger scale than Figs. 1 and 2.

Referring to the drawings in a more particular description, it will be seen that the coaster illustrated has a rectangular frame which is composed of two side pieces 7 and two end pieces 8 preferably formed as shown of angle iron with the horizontal web of the angle toward the top. At each of the four corners the end of one side piece 7 and of one end piece 8 is fitted to a corner piece 9. Each corner piece has a flat horizontal plate 10, substantially square. Its two outer adjacent edges are provided with downwardly extending flanges 11 and 12 connected at the outer corner preferably by a rounding flange 13, which extends outward more than flanges 11 and 12 so as to provide shoulders 14 and 15 where the rounding flange 13 meets the straight flanges 11 and 12. The side angle piece 7 has its horizontal web rested flat upon the upper surface of the plate 10 of the corner piece, while the vertical web of the side piece is fitted against the shoulder 15. Similarly the horizontal web of the end pieces is rested flat upon the upper surface of the plate 10 and the end of the vertical web of the end angle piece bears against the shoulder 14. Preferably as indicated in

Fig. 4 the corner piece 9 is raised on its upper surface between the flange 13 and the adjacent edges of the horizontal web of the side and end pieces so as to have the corner

piece on the same level as the upper surface of the side and end angle irons, and provide shoulders 16 and 17 on top of the corner piece against which may be fitted the ends 5 of the horizontal webs of the end angle piece 8 and side angle piece 7. The end piece 8 is rigidly secured in position relative to the corner piece by two rivets 18 passing through the horizontal web of the said angularly-shaped end piece 8 and the plate 10 of the corner piece. Similarly the side angle piece 7 is rigidly secured to the corner piece 10 by rivets 19 passing through the horizontal web of the side piece and the plate 10 of the 15 corner piece.

It will be obvious from the construction of the corner joint above described that a smooth and very rigid corner is provided and that the weight carried by the frame is 20 transmitted direct to the corner pieces and is not borne simply by the fastening members; similarly that strain inward upon the side and end pieces of the frame incident to the way the fabric is supported therefrom 25 transmits no appreciable strain to said rivets or other fastening members. It will be understood that the vertical webs of the side pieces 7 and end pieces 8 are outside the corner piece and bear flat upon the flanges 12 30 and 11 respectively.

Each corner piece 9 has on the two inner edges of the plate 10 projecting ears 20 and 21, provided with apertures therethrough 22 and 23 respectively for the purposes hereinafter mentioned.

The body-supporting surface of the coaster is composed of a strip of strong flexible fabric 24 such as wire-link fabric of any desired form suitably secured to the frame. 40 The preferred form, however, is to have said strip of link fabric 24 positively fastened to one end of the coaster as by the ends of the links at that end being hooked through apertures 25 in the horizontal web 45 of the end piece 8, while the other end is yieldingly connected to the other end piece 8 as by means of strong helical springs 26 connected at their inner ends to that end of the link fabric, while the other ends of the 50 helical springs are hooked to the end piece 8 as by the hook on the helicals being inserted through apertures 27 on the end piece 8. In order, however, to prevent the helicals 26 from standing up too high as would be the 55 case if the helicals rested on top of the plate 10 of the corner piece, the helical nearest the side piece 7 is hooked into the aperture 22 of ear 20 and the next helical is hooked into the aperture 23 of ear 21. At the other end 60 of the coaster the link of wire fabric nearest each corner is hooked into the aperture 22 of ear 20, but the next inward link of the fabric may be hooked into its regular aperture

25, since the wire of said link fabric will not extend above the rest of the links.

It will be seen that the use of this strong metallic fabric for the purpose of supporting the body of the workman is a great advantage over the use of a rigid sheet of material such as wood or metal. As the people 70 using the repair coaster often have to be on their back or on their side upon the coaster for considerable periods at a time, anything conducing to the comfort of the person is an advantage.

Furthermore, the providing of yieldingly supported fabric is an advantage in providing the body a surface that is much more yielding and convenient for the user. Preferably the strip of link fabric will be supported midway of its length by a cross member such as two loops 28 hooked into the opposite horizontal webs of the side pieces, the inner ends of said loops being connected by a helical spring 29, which is so tensioned as 85 to aid in keeping the fabric thereabove level with the frame.

Each corner of the coaster is provided with a strong caster 30, preferably ball bearing, and secured to the coaster by having the 90 caster plate 31 fastened directly to the bottom surface of the plate 10 of the corner piece. These casters are commonly stock or come in fixed sizes, with definite sizes of caster plate 31, with said caster plate perforated with holes 32 arranged toward the corner of the rectangular caster plate. Accordingly I have formed the specially made corner piece 9 to readily fit the caster plates by having the two pair of holes toward the 95 outer edges of the plate portion 10, spaced apart the same distance as are the two holes upon either end of the caster plate. In this way the two rivets that go through the side piece 7 or the end piece 8 and through a 100 corner piece may be utilized to go through one pair of end holes in the caster plate, no matter whether the caster plate is arranged crosswise or longitudinally of the coaster. The rivets passing through the two holes at 105 the other end of the caster plate simply pass through the caster plate and one of the inner edges of the corner plate 10. By having one 110 of the inner edges of the plate 10 provided with two holes matching the inner pair of holes upon the caster plate and turning the 115 caster plates two longitudinally and two crosswise, a single form of corner piece may be utilized for all four corners of the coaster instead of requiring as would otherwise be 120 the case two or more specially formed corners, each adapted for only one or two positions.

What I claim as new and desire to secure by Letters Patent is:

In an auto repair coaster, the combination

of a rectangular rigid frame composed of angle iron side pieces and end pieces and corner pieces against the outer edges of which bear the flanged side and end pieces, said corner pieces having a recessed portion on their lower face, casters mounted on the recessed portion of the bottom of said corner

pieces, a supporting surface of flexible material stretched on said frame and shoulders on said corner pieces against which fit the 10 extremities of said side and end pieces.

In witness whereof I have affixed my signature this 29th day of February, 1916.

WILLIAM B. FOSTER.
